JACK SNARCK, OF NEW YORK, N. Y.

FAGOTING EMBROIDERY AND METHOD OF MANUFACTURING SAME

Application filed December 26, 1931. Serial No. 583,830.

REISSUED

This invention relates to improvements in fagotting embroidery and methods of manufacturing same.

One of the objects of this invention is to provide a method and apparatus for producing fagotting embroidery with great speed and economy; to produce a method whereby a subsequently dischargeable fabric is employed to provide an interposed protective foundation or element between the fagotting cross-threads and the embroidery fabric so as to enable the cutting and edge-folding tools to be rapidly and quickly manipulated to sever or slit fabric traversely of such cross-threads and to fold over the severed edges without danger of severing or otherwise injuring the cross-threads or stitches; to provide a method and apparatus by the use of which the severed edges of slit in the embroidery fabric may be, in one operation, neatly and quickly opened up, folded over and initially ironed in preparation for subsequent pressing and fastening down.

With these and other objects in view, the invention comprises the combination of members and arrangement of parts so combined as to co-act and co-operate with each other in the performance of the functions and the accomplishment of the results herein contemplated, and comprises in one of its adaptations the species or preferred form illustrated in the accompanying drawings, in which:—

Fig. 1 is a view in plan of a finished piece of fagotting embroidery embodying my invention;

Fig. 2 is a section on the line 2—2 of Fig. 1, looking in the direction of the arrow;

Fig. 3 is a view in plan of the reverse side of a piece of material or fabric mounted upon vanishing fabric and stitched with a fagotting stitch;

Fig. 4 is a section on the line 4—4 of Fig. 3 looking in the direction of the arrow;

Fig. 5 is a view similar to Fig. 3 showing the embroidered material slit intermediate the cross-threads of the fagotting stitch;

Fig. 6 is a view similar to Figs. 3 and 5 showing the edges of the slit fabric initially

folded by a novel turning and pressing or folding element;

Fig. 7 is a side elevation of a novel tool employed in slit-opening, edge turning and initial hot-pressing or ironing;

Fig. 8 is a bottom view in plan of the tool shown in Fig. 7;

Fig. 9 is an enlarged detail view of the fagotting embroidery stitch preferably employed by me.

Referring now to these drawings which illustrate a preferred embodiment of my invention, 1 indicates a single, unfolded piece of fabric or material to be embroidered, which I shall hereinafter call "an embroidery fabric", 2 indicates a piece of heat-dischargeable fabric, adapted on subjection to heat to be discharged and to be brushed away, and which, in the preferred embodiment of my invention, I utilize as a protective foundation fabric or protective element. As illustrated in Figs. 3 and 4, the embroidery fabric is superposed over the heat-dischargeable fabric with the front face of the embroidery fabric abutting the dissolvable fabric, and a fagotting-embroidery stitch, preferably such as shown in Fig. 9, is stitched through both of said fabrics to produce a suitable design of any bent or curvi-form configuration and composed of two rows of parallel longitudinal stitches having cross-threads extending between the same and all formed or arranged in a single plane. My preferred stitch, 3,

comprises a chain-stitch portion 3', fagotting cross-threads 3a and connecting stitch portion 3b. When this stitch is made in the superposed embroidery fabric and dischargeable fabric, only the cross-threads 3a pass through the fabric and extend beneath or on underside or bottom of the dissolvable fabric 2 and these fagotting embroidery threads will thus, as hereinafter described, be protected by this dischargeable fabric, which is stiff and tough, during the further operations on the fabric.

The stitch 3 being made through the embroidery fabric and the protecting heat-dischargeable element 2, the portion of embroidery fabric extending over the cross-threads and between the parallel edge-stitch portions

3' and 3b may be slit, as shown at 4 in Figs. 5 and 6 by a pair of scissors, a knife or in any other suitable manner, and in this slitting operation, the heat-dissolvable protective element 2, being disposed between the fabric 1 and the cross-threads 3a will serve as a protective foundation to prevent engagement and severing of cross threads by the severing tool, thus permitting greater speed 10 in manufacturing than would otherwise be possible.

After the fabric is slit as shown at 4 in Figs. 5 and 6, I open up the slit, turn over the edge and initially iron or hot-press the 15 same, and for this purpose, I utilize a novel device combining in one tool a slit-opener, edge turner and initial hot presser.

The slit-opening portion of this tool is inserted in the slit and upon sliding the tool 20 along through the slit on the dischargeable fabric I turn or fold outwardly and downwardly in opposite directions the marginal edges adjacent to the slit and in the same operation I iron or hot-press these edges so 25 as to cause such edges to initially retain their folded position.

As illustrated in Figs. 6 to 8 inclusive, I utilize a tool having a pointed and upwardly inclined portion which is preferably semi-30 conic in configuration and is adapted for ready insertion in the slit to cause a raising of the fabric edges and this pointed semi-conic or upwardly-inclined portion merges with another portion for turning down such 35 edges, and said tool also provides means for the initial pressing or ironing of such edges so as to cause them to maintain their folded condition.

As illustrated, my novel tool 5 includes a 40 metallic head 6, having a pointed insertion portion 7 provided with an upwardly-inclined surface 7' merging with a reversely-inclined wall portion 7a serving as a turning portion. Said wall portion 7a is slightly inclined in the opposite direction and has a bevelled edge 7b. This bevel-edged wall 7a preferably surrounds the semi-conic pointed nose, constituting a major circumference merging at its lower end with a flat bottom 50 portion 7c which preferably extends outwardly to provide pressing wing portions beneath which the fabric margin is lead to permit hot pressing. This flat surface also preferably merges or extends to the point 7. 55 Suitable means is employed for supplying heat to the tool 5 and in the embodiment shown, the head 6 is provided with a shank 6' which screws into a handle 8. The handle 8 has a suitable socket 8' and contains an 60 electric heating element of conventional form.

In using the tool 5, the pointed insertion portion 7 is, as above indicated, inserted in the slit, the flat portion 7c being passed along 65 between the edges 3'-3b of the stitch 3 and

over the protecting fabric 2 and forming a guide for the semi-conic opening surface 7'. This portion 7' lifts and opens the marginal edges of the slit and these edges upon reaching the bevelled wall 7a are turned outwardly and downwardly beneath the outer wing portions 7d which merges with the flat portion 7c. The heating of the heating element thereupon supplies the necessary heat and pressing or ironing means to initially retain said folded portion in folded condition.

After initially folding down the marginal edges as above described, I apply on the reverse side of the fabric beneath the folded edges of the slit a conventional fastening material such as rubber, which is sprayed beneath said initially folded marginal edges by the use of conventional spraying apparatus.

The embroidered fabric is then, preferably in one operation or simultaneously, subjected to heat and pressure which not only securely fastens down the said marginal edges but also serves to discharge the protective dischargeable fabric which, after such pressing and heating may be brushed away to leave the open fagoting channel with the cross-threads only of fagoting stitches exposed at the front side as shown in Fig. 1, while the parallel chain and connecting stitch portions 3', 3b are concealed on the reverse side by the fastened down marginal edges of the slit.

As many changes could be made in the above construction and many apparently widely different embodiments of this invention could be made without departing from the scope thereof; it is intended that all matter contained in the above description or shown in the accompanying drawings shall be interpreted as illustrative and not in a limiting sense.

Having described my invention, I claim:

1. The method of manufacturing fagoting embroidery consisting in embroidering a single piece of material with two rows of parallel stitches and cross-threads extending between such stitches, slitting the fabric between such parallel rows of stitching, and in a single operation folding down the edges of the slit portion in opposite directions over the parallel rows of stitching to conceal the same and applying heat to said edges to retain the same in folded position.

2. The method of manufacturing fagoting embroidery consisting in taking a piece of fabric to be embroidered, superimposing the same on a piece of fabric dischargeable by heat, applying a fagoting embroidery stitch through said fabric to be embroidered and through said dischargeable fabric to cause longitudinal parallel rows of stitches to be exposed on one side of said embroidered fabric and cross stitches to be exposed on the opposite side of the dischargeable fabric, slit-

ting said embroidered fabric between said exposed two longitudinal rows of stitches and above said dischargeable fabric, folding the edges of the slitted portion downwardly to conceal the rows of stitches and simultaneously turning over the edges of the slitted portion and ironing the same in a single operation to initially retain the same in folded condition and then simultaneously subjecting said fabric to heat and pressure to discharge the dischargeable material and to press the folded edges.

3. The method of manufacturing fagoting embroidery consisting in taking a piece of fabric to be embroidered, superimposing the same on a piece of fabric dischargeable by heat, applying a fagoting embroidery stitch through said fabric to be embroidered and through said dischargeable fabric to cause parallel longitudinal rows of stitches to be exposed on one side of said embroidery fabric and cross-strokes to be exposed on the opposite side of the dischargeable fabric, slitting said embroidery fabric between said exposed two longitudinal rows of stitches and above said dischargeable fabric, folding the edges of the slitted portion downwardly to conceal the longitudinal rows of stitches and in the same operation simultaneously turning over the edges of the slitted portion to retain such edges in initially folded condition, spraying under the folded edge portions a fastening material and then simultaneously subjecting said fabric to heat and pressure to discharge the dischargeable material and to press the folded edges.

4. Fagoting embroidery embodying, in combination, a single piece of fabric, a stitch embroidered in said fabric in an ornamental curvi-form design of any suitable configuration and comprising two rows of parallel longitudinal stitches both arranged completely on one face of the fabric and cross-threads passing through the fabric to the opposite face of the fabric, said fabric having an open channel between said parallel longitudinal stitches to expose the cross-threads and having the edges of the fabric at each side of the channel folded and fastened down over the said rows of longitudinal stitches to conceal the same.

In witness whereof I have signed my name to the foregoing specification.

JACK SNARCK.
